UNITED STATES PATENT OFFICE.

CHRISTIAN AALBORG, OF PITTSBURGH, PENNSYLVANIA, ASSIGNOR TO WESTINGHOUSE ELECTRIC & MANUFACTURING COMPANY, A CORPORATION OF PENNSYLVANIA.

THERMAL RELAY.

Application filed June 23, 1925. Serial No. 38,963.

My invention relates to temperature control devices and particularly to thermal relays.

One object of my invention is to provide 5 a relatively simple, compact and inexpensive thermally-responsive device.

Another object of my invention is to provide a thermal relay in which the pressure between cooperating contact members shall 10 be increased preparatory to causing them to be disengaged with a snap action.

In practicing my invention, I provide a thermally-responsive means and a resilient energy-storing member actuated thereby, 15 having associated therewith a member whose shape is changed by the resilient member whereby engagement or disengagement of cooperating contact members is effected with a snap action.

20 In the single sheet of drawings,

Figure 1 is a top plan view of a device embodying my invention.

Fig. 2 is a view, in side elevation, thereof.

25 Fig. 3 is a view in section therethrough, taken on the line III—III of Fig. 1.

Fig. 4 is a top plan view of two cooperating toothed sector members.

Fig. 5 is a view in side elevation thereof.

30 Fig. 6 is a top plan view of a member of modified form associated with the device embodying my invention, and

Fig. 7 is a top plan view of a modified form of device embodying my invention, illustrated schematically only.

35 Referring more particularly to Figs. 1 to 5, inclusive, a thermal relay 11 comprises a suitable base member 12 that is preferably of electric-insulating material and that may be substantially circular in contour.

40 Two supporting members 13 and 14 are mounted in spaced relation on the base plate 12 and are constituted by metal rod members, the lower ends of which extend into the base 12 and are so mounted and held therein that they may have a turning movement relative thereto. The upper ends of the respective rods 13 and 14, are provided with a diametrically extending slot to receive one end of spirally wound bimetallic elements 15 and 16. The ends of the members 15 and 16 are secured in the members

13 and 14 by any desired method, such as by brazing or soldering or by a screw clamping means.

55 An energy-storing member 17, constituted by a spring member of substantially U-shape, is so located relatively to the bimetallic elements 15 and 16 that the outer ends of the respective bimetallic members may 60 be secured to the side portions of the member 17 by suitable rivets 18. The ends of the member 17 are made in the form of knife edges in order that a toggle member comprising two arms 19 and 21 may be 65 operatively associated therewith. The outer ends of the arms 19 and 21 are made in expanded form and provided with a slot or groove to receive the knife-edge ends of the member 17. The inner ends of the arms 70 19 and 21 are so shaped as to permit of their being pivotally connected by a pin 22.

A pair of stationary contact members 23 and 24 are suitably mounted on the upper surface of the base member 12 and are severally provided with upstanding contact portions 25 and 26 that are normally operatively engaged by contact members 27 and 28 that are mounted on the arms 19 and 21, here shown as machine screws, each provided 80 with a lock nut to permit of securing the contact screws in a predetermined position after they have been adjusted.

75 Means for adjusting the initial position of the two spirally wound bimetallic members 85 15 and 16 whereby the operating temperature thereof may be adjusted, comprises a member 29 having its lower surface secured against the upper surface of the base member 12 and having an upwardly extending 90 portion that is provided with a screw threaded opening 31 extending therethrough substantially parallel to the surface of the base plate 12. An adjusting screw 32 having a knurled head 33 extends through the 95 opening 31 and has an annular groove 34 adjacent to the outer end thereof.

Toothed sectors 35 and 36 are secured to the respective supporting members 13 and 14, the members being brazed or soldered 100 together in order that a turning movement of the members 35 and 36 may effect a corresponding turning movement of the members 13 and 14 and of the inner

end of the bimetallic members. An up-standing lug 37 having an elongated slot 38 in its upper end is rigidly secured to one of the sector members, for instance, member 36. The annular groove 34 of the member 32 fits into the slot or recess 38, thereby permitting of varying the positions of the sector members the supporting posts 13 and 14, and of the inner ends of the bimetallic members by a turning movement of the screw threaded member 32.

While I have illustrated a toggle member in Fig. 1 of the drawing, I do not desire to be limited thereto as I may substitute a spring member therefor.

Fig. 6 illustrates a spring member 39 that is initially bent to arcuate form and that has located thereon contact members 41 and 42 secured thereto. When the member 39 is used, it may be desirable to provide the knife edges on the spring member rather than on the member 17. It is understood that the design and construction of the member 39 of the member 17 is such that they will properly cooperate as will be hereinafter set forth.

I have illustrated a modification in Fig. 7 of the drawing, which illustrates a portion only of the parts constituting a complete thermal relay. A supporting member 43 is of substantially U-shape, having upstanding portions 44 and 45 to which may be secured two substantially straight bimetallic elements 46 and 47 at substantially the middle points thereof. An energy-storing or spring member 48, that is of substantially circular shape is provided. A toggle joint operatively associated with the member 48 comprises arms 49 and 51, the inner ends of which are pivotally connected by a pin 52. Adjustable contact members 53 and 54 are provided for the respective arms 49 and 51, which normally engage fixed contact members 55 and 56.

Any suitable or desired means for effecting an operative connection between the outer ends of the bimetallic elements 46 and 47 and the member 48 may be provided, such, for instance, as by reducing the lateral width of the outer ends of the members 46 and 47 and causing them to project through suitable openings provided in the member 48. A loose connection between the bimetallic elements and the spring member 48 is desirable but there should be no end play between the two co-operating portions.

Referring more particularly to the device illustrated in Fig. 1 of the drawing, the bimetallic elements 15 and 16 are so arranged as regards the metal strip having the higher coefficient of expansion with an increase of temperature, that both spirals will tend to open or to unwind, thereby moving the member 17 downwardly in the plane of the paper as the temperature increases. The

member 17 is free to move under the influence of the force exerted by the bimetallic elements 15 and 16, as it is substantially entirely supported by the outer ends thereof. As the temperature increases, the force exerted by the members 15 and 16 increases and member 17 is moved downwardly storing energy therein and increasing the pressure between the co-operating contact members 25 and 27 and 26 and 28. This pressure between the cooperating contact members increases until the member 17 has moved far enough to straighten out the toggle joint constituted by the arms 19 and 21, after which the toggle will snap into the position illustrated by the broken lines in Fig. 1, the inner ends thereof engaging an upstanding portion of a member 57 provided for that purpose. When the toggle is in the position illustrated by the broken lines, a circuit that had been established through the cooperating contact members and the toggle has been interrupted. Conductors 58 and 59, having one end thereof connected to the terminal members 23 and 24, permit of connecting them to a suitable source of supply and to a device to be controlled thereby.

When the temperature to which the relay 11 is subjected has been reduced, as by the interruption of a heating circuit as was hereinbefore described, the bimetallic elements will tend to move in the opposite direction and the spring member 17 will be moved in the opposite direction, that is, in a direction toward the stop member 57. As soon as the toggle has been so moved, particularly the outer ends thereof that the two arms are located in a straight line, the toggle will snap over to the other position, which is that shown in Fig. 1 of the drawing.

The toothed sectors 35 and 36 provide a means for varying the operative temperature at which disengagement of the cooperating contact members is effected. A turning movement of the screw 32, in the member 29, causes a turning movement of the two sectors and therefore of the supporting posts 13 and 14. This varies the position of the inner ends of the bimetallic elements relatively to the outer ends, thereby varying the initial tension and varying also the temperature at which actuation of the device will occur. As hereinbefore stated, I may use a spring member 39 in place of the toggle, the action of the device with such spring member being substantially the same as described above.

The modified form of device illustrated more particularly in Fig. 7 of the drawing operates in substantially the same manner as was hereinbefore described for the other form of device. The two bimetallic elements are located similarly as regards the

high expansion metal, that is, both bimetallic elements move in the same direction under the influence of a temperature increase or a temperature decrease. If the

- 5 temperature surrounding the device illustrated in Fig. 7 increases, the bimetallic members 46 and 47 will bow upwardly, thereby initially increasing the pressure between the co-operating contact members
 10 until the toggle has been straightened, after which any further movement of the energy-storing spring member 48 will cause a sudden disengagement between the co-operating contact members, the inner end portions
 15 of the arms 49 and 51 striking a stop member 61 provided for that purpose. The bimetallic members 46 and 47 will tend to move in the opposite direction after the temperature thereof is reduced and the
 20 same sudden disengagement between the stop member and the toggle will be effected, while the engagement between the co-operating contact members will be made with a snap action.

- 25 The device embodying my invention thus provides a relatively simple and compact thermal relay that may be employed to control the temperature of a device or apparatus, that will be so moved as to cause engagement or disengagement of the co-operating contact members with a snap action only, and that will increase the pressure between the co-operating contact members until the instant of disengagement
 30 35 which, as above stated, is effected with a snap action.

Various modifications may be made in the device embodying my invention without departing from the spirit and scope thereof,
 40 and I desire that all such modifications shall

be included in the appended claims which are to be limited only by the prior art.

I claim as my invention:

1. In a thermal relay, the combination with a bimetallic member, of a spring member of substantially U-shape supported and actuated thereby, and means extending between the ends of said spring member and actuated thereby with a snap action only.

2. In a thermal relay, the combination with a plurality of bimetallic members, of a spring member of substantially U-shape having the outer ends of the bimetallic members secured thereto and being supported thereby, co-operating contact members, and means supporting certain of said contact members operatively associated with said spring member, carried thereby and actuated by said spring member with a snap action only upon the occurrence of a predetermined temperature in said bimetallic members.

3. In a thermal relay, the combination with a plurality of spirally-wound bimetallic members, of a spring member of substantially U-shape having the outer ends of the bimetallic members secured thereto and supported thereby, means operatively associated with said spring member, carried thereby and actuated by said spring member with a snap action only upon the occurrence of a predetermined temperature in said bimetallic members, and means operatively associated with said bimetallic members for varying the value of said predetermined temperature.

In testimony whereof, I have hereunto subscribed my name this 11th day of June, 1925.

CHRISTIAN AALBORG.
